DESIGN FOR A TRAVELING LAWN SPRINKLER

Birger J. Borgerson, Chicago, Ill.

Application January 17, 1947, Serial No. 136,194

Term of patent 7 years

(Cl. D91—1)

To all whom it may concern:

Be it known that I, Birger J. Borgerson, a citizen of the United States, residing at Chicago, in the county of Cook and State of Illinois, have invented a new, original, and ornamental Design for a Traveling Lawn Sprinkler, of which the following is a specification, reference being had to the accompanying drawing, forming a part thereof.

Figure 1 is a fragmentary top plan view of a traveling lawn sprinkler, showing my new design, with the sprinkler member broken away for convenience of illustration; and

Figure 2 is a side view thereof.

I claim:

The ornamental design for a traveling lawn sprinkler, substantially as shown.

B. J. BORGERSON.
